UNITED STATES PATENT OFFICE.

HAROLD DE OLANETA, OF NEW HAVEN, CONNECTICUT, ASSIGNOR TO WINCHESTER REPEATING ARMS COMPANY, OF NEW HAVEN, CONNECTICUT.

DRY CELL.

Application filed August 18, 1920. Serial No. 404,379.

This invention relates to dry cells, and while it is not limited in its application to that purpose, it is primarily intended for employment in connection with small dry cells such as used for electric flash lights. It may also be applicable to cells which are not dry cells.

The invention pertains more especially to the closure at the upper end of the dry cell cup and the means for supporting the same in position.

One of the primary objects of the invention is the provision of a simple, inexpensive, efficient and easily assembled end closure construction for dry cells.

Another object is to furnish improved means for positioning and securing within the mouth portion of the cup a disk or plug of insulating material formed prior to its insertion in the cup.

Another purpose which I have in view is the forming of the closure member from a novel material which is particularly adapted for this use.

To these and other ends the invention consists in the novel features and combinations of parts to be hereinafter described and claimed.

In the accompanying drawings:

Fig. 1 is a vertical central section of a dry cell embodying my improvements;

Fig. 2 is an elevation partly in section of a cell of somewhat modified form;

Fig. 3 is a fragmentary section on an enlarged scale of certain parts shown in Fig. 1; and

Fig. 4 is a detailed perspective view of the end plug made in accordance with the principles of my invention.

I have shown my improvements applied to a small dry cell of the type commonly employed in connection with pocket flash lights. The cell comprises a drawn zinc cup 10, forming one of the electrodes. Within the cup is a cartridge 11 of a suitable depolarizing material, surrounding and adhering to a carbon pencil 12, which serves as the second electrode. The cartridge 11 is of less height than the cup and is usually enclosed in a porous wrapper 13. The body of paste 14 lies between the side surface of the cartridge and the side wall of the cup and serves as a carrier or vehicle for the electrolyte. A suitable centering device 15 is preferably employed for centering the

cartridge within the bottom portion of the cup.

The wall of the zinc cup is displaced in an inward direction, for example, by means of a continuous annular crimp or groove 16 that may readily be formed by spinning. The groove is created on the surface of the cup and the corresponding annular shoulder or bead projects within the cup at about the level of the upper surface of the cartridge 11. A closure member or plug 17 rests on this shoulder or bead and on the cartridge and seals the cell. This closure member is preferably made of a suitable insulating material, as an artificial resin, such as bakelite, condensite (condensation product of a phenolic substance with an aldehyde) or the like. In the form of cell shown in Fig. 1, this closure member of bakelite, as shown, rests upon the cartridge 11 and upon the shoulder 16. The top of the metal at the edge of the zinc cup is spun over the disk or closure member 17, as at 18, so as to overlie the top surface of the plug near the periphery thereof. This is a very efficient and preferred way of securing the plug in position on the cartridge and shoulder, although this may be accomplished in any desired manner. The carbon pencil 12 is usually provided with a contact cap 20 on its upper end, which may be of brass or any suitable material.

In the form of cell shown in Fig. 2, the shoulder or bead 16, which is formed upon the wall of the cup, is shown to be a slight distance above the level of the upper surface of the cartridge and in this way provision is made for a gas chamber 19 between the cartridge and paste in the cell and the closure plug 17. The cell, as shown, may or may not be constructed with this gas chamber.

The plug or closure member formed of an artificial resin such as bakelite, condensite or the like, has been found to be very advantageous in the construction of cells of this character. The plug made of such material is practically incapable of alteration after its manufacture. It will not warp nor absorb moisture from the cell or from the atmosphere, and constitutes an effectual and expedient closure member for these cells. The particular type of dry cell, the particular constituents of the materials used are, of course, not essential to this invention. It will be apparent that a closure

member of such material may be used in cells which are not made precisely like the preferred form herein described, and may be secured in the cell in any desired manner.

5 While I have shown and described a preferred form of my invention, it will be apparent that the same is not limited to the exact details set forth, but is capable of many modifications and variations which lie 10 within the spirit of the invention and within the scope of the appended claims.

What I claim is:

1. In a dry cell, a metallic cup, a cartridge 15 of less height than the cup located therein and having an upwardly projecting electrode, an exciting paste interposed between the cartridge and the side wall of the cup, the wall of said cup being formed to provide an annular, inwardly projecting shoulder 20 at a point substantially at the level of the upper surface of the cartridge, and a pre-formed plug inserted in the cup by a longitudinal thrust, said plug having an opening 25 to receive the projecting end of the electrode, having its lower surface resting upon said shoulder and the cartridge and having its upper edge adjacent the upper end of the cup, the upper edge of the cup being spun over the upper surface of the closure 30 member.

2. In a dry cell, a cup, a cartridge of less height than the cup located therein and having an upwardly projecting electrode, an exciting paste interposed between the cartridge and the side wall of the cup, and a preformed plug of insulating material inserted into the cup by a longitudinal thrust and substantially filling the space between the cartridge and the upper end of the cup, said cup wall being provided with inwardly extending projections both above and below the plug.

3. In a dry cell, a cup, a cartridge of less height than the cup located therein and having an upwardly projecting electrode, an exciting medium interposed between the cartridge and the side wall of the cup, a pre-formed plug of insulating material inserted within the upper end portion of the cup and having an opening to snugly receive the projecting end of the electrode, said plug substantially filling that part of the cup above the cartridge, and said cup wall being provided with inwardly extending annular projections both above and below said plug to secure the latter in place, said projection below said plug lying substantially at the level of the upper surface of the cartridge.

In witness whereof, I have hereunto set my hand on this 31st day of July, 1920.

HAROLD DE OLANETA.
